UNITED STATES PATENT OFFICE.

LEWIS C. NORTON, OF CHICAGO, ILLINOIS, ASSIGNOR TO NORTON DOOR CHECK COMPANY, OF CHICAGO, ILLINOIS, A CORPORATION OF WEST VIRGINIA.

DOOR-OPERATING MECHANISM.

1,124,940

Specification of Letters Patent.

Patented Jan. 12, 1915.

Application filed May 23, 1914. Serial No. 840,638.

To all whom it may concern:

Be it known that I, Lewis C. Norton, a citizen of the United States, residing at Chicago, county of Cook, State of Illinois, 5 have invented an Improvement in Door-Operating Mechanism, of which the following description, in connection with the accompanying drawing, is a specification, like characters on the drawing representing 10 like parts.

This invention relates to door-operating mechanism for sliding doors and particularly to that type of mechanism which involves a toggle-lever device connected to 15 the door and to a fixed abutment and which is straightened when the door is closed, and a handle connected to the toggle-lever mechanism and arranged so that the initial movement of the handle will break the toggle 20 lever and continued movement of the handle will open the door.

In some devices of this nature the handle is so connected to the toggle-lever mechanism that it has a continuous movement relative to the door while the door is opening 25 or closing, and in devices of this nature it is a desideratum that the handle should have as little movement as possible relative to the door.

30 The object of my invention is to provide a novel mechanism which meets these conditions.

In order to give a proper understanding of my invention I have illustrated in the 35 drawings a selected embodiment thereof which will now be described.

The figure shows a device embodying my invention.

1 designates a sliding door which may be 40 the door of an elevator well or any other sliding door. This door has pivotally connected thereto at 2 one member 3 of a toggle-lever device, the other member 4 being pivotally connected at 5 to a fixed abutment and being pivotally connected to the 45 member 3 at 6.

7 is a combined door closer and check of any suitable description which is connected to an arm 8 extending laterally from the 50 member 4. The parts thus far described are more or less commonly used in connection with elevator doors for operating the door, the door closer and check 7 operating automatically to close the door when open

and the toggle-lever members 3 and 4 being in alinement with each other when the door is closed thereby locking the door in such position. In order to open the door the toggle lever must first be broken and this is accomplished herein by a handle 9 60 pivotally connected to the door at 10.

The handle has a U-shaped portion or reverse bend 11 therein and a link 12 is pivotally connected to the bend, as at 13. This link is pivotally connected at 14 to 65 an arm 15 extending laterally from the member 3 near one end thereof. When the parts are in the full line position Fig. 1 the door is closed and locked in its closed position by reason of the alined position 70 of the members 3 and 4.

To open the door the operator moves the handle in the direction of the arrow *a* and the first movement of the handle operates through the link 12 and arm 15 to raise 75 the toggle-lever member 3, thus breaking the toggle lever. Continued movement of the handle 9 in the direction of the arrow opens the door, as will be obvious. Owing to the particular construction of the handle 80 9 and the manner of connecting it to the laterally-extending arm 15 by the link 12, said handle has a comparatively small swinging movement relative to the door while the door is being opened or closed. 85

While I have illustrated a selected embodiment of my invention I do not wish to be limited to the constructional features shown.

I claim:

1. The combination with a sliding door, of toggle-lever door-operating mechanism comprising two members pivotally connected together and to the door and a fixed abutment, respectively, an arm extending 95 laterally from the first-named member between its ends, a handle pivoted to the door, said pivot being in line with said arm when the door is closed, and a link pivotally connecting said handle and arm. 100

2. The combination with a sliding door, of toggle-lever door-operating mechanism comprising two members pivotally connected together and to the door and a fixed abutment, respectively, an arm extending laterally from the first-named member between its ends, a handle pivoted to the door said pivot point being in line with said arm 105

when the door is closed and having a U-shaped portion, and a link connecting said U-shaped portion to said arm.

3. The combination with a sliding door, 5 of toggle-lever door-operating mechanism comprising two members pivotally connected together and to the door and a fixed abutment, respectively, said members being in alinement with each other when the door 10 is closed, an arm extending vertically from the first-named member between its ends, a handle pivoted to the door above said arm

and said pivot being in line therewith, said handle having a U-shaped portion and a link pivotally connecting said U-shaped portions to the end of said arm. 15

In testimony whereof, I have signed my name to this specification, in the presence of two subscribing witnesses.

LEWIS C. NORTON.
